[57] CLAIM

The ornamental design for a fitting for venetian blinds,
as shown and described.

DESCRIPTION

FIG. 1 is a top, front and left side perspective view of a
fitting for venetian blinds showing my new design;

FIG. 2 is a top plan view thereof;

FIG. 3 is a left side elevational view thereof, the right
side being a mirror image.

The bottom is plain and unornamented.

FIG. I

FIG.2
